(57) CLAIM

I claim the ornamental design for a skin massager applicator head, as shown and described.

DESCRIPTION

FIG. 1 is a front view of a skin massager applicator head showing my new design.

FIG. 2 is a top plan view of FIG. 1:

FIG. 3 is a right side view of FIG. 1:

FIG. 4 is a left side view of FIG. 1:

FIG. 5 is a bottom plan view of 1:

FIG. 6 is a perspective view of FIG. 4:

FIG. 7 is a bottom perspective view of FIG. 3; and,

FIG. 8 is a perspective view of FIG. 5:
